Specification for Design.

Patented Aug. 2, 1921.

Application filed August 2, 1920. Serial No. 400,874. Term of patent 14 years.

To all whom it may concern:

Be it known that we, ROBERT G. CLYNE, a subject of the King of Great Britain, and KITTY RAYBURN, a citizen of the United States of America, residing in St. Louis, in the State of Missouri, have invented a new, original, and ornamental Design for a Washing-Machine Casing, of which the following is a specification, reference being had to the accompanying drawing, forming a part thereof, in which—

The illustration is a perspective view of the washing machine embodying our invention.

We claim:

The ornamental design for a washing machine casing, as shown.

In testimony whereof, we have signed our names to this specification.

ROBERT G. CLYNE.
KITTY RAYBURN.
